POSITIVE DISAPPEARING KNOCKOUT
PIN MECHANISM

Dominic Maniaci, Detroit, Mich.

Application January 14, 1948, Serial No. 70,871

3 Claims. (Cl. 113—50)

1

This invention relates to machines such as punching or forming presses and, more particularly, to means for insuring prompt and effective displacement of work from the seat of operation after the machine has completed its working stroke and while it is performing its return stroke. Thus, by the time the machine has completed its return stroke preparatory to performing the next working stroke, the bed or die will have been cleared for reloading with a new work unit and delays and difficulties heretofore experienced in such machines, due to work having to be pried or otherwise loosened and removed therefrom, are avoided.

An important object of the invention is to provide the die shoe or work table of such a machine with a disappearing pin reciprocal beneath the work to operate as an ejector therefor, and operating means for said pin adapted to effect its ejecting movement during a portion of the return stroke of the machine, and to be released at a predetermined point in said return stroke whereby it may be retracted through the die shoe or table of the machine under the control of means provided for that purpose.

A further object is to provide a trigger or detent mechanism of a unique nature adapted to control the timing of the operation of said disappearing ejector pin in desired synchronism with the operating strokes of the machine.

Still further objects and advantages subsidiary to the aforesaid objects, or resulting from the construction or operation of the invention as it may be carried into effect, will become apparent as the said invention is hereinafter further disclosed.

In carrying the said invention into effect, I may adopt a novel construction and arrangement of parts hereinafter described, by way of example, having reference to the accompanying drawing, 40 wherein:

Figure 1 is a partial elevation of the die shoe of a forming press to which my improved work-ejecting mechanism is attached, parts of the mechanism being shown in section for clarity of illustration; and

Figure 2 is a similar view to Figure 1 illustrating the parts in a different position of operation.

Similar characters of reference indicate similar parts in both figures of the drawing.

10 indicates the stationary die shoe of a press and 11 a vertically moveable punch or die holder; 12 and 13 indicating, for the sake of example, lower and upper die elements adapted to close the seam of a work unit 14.

2

The punch or die holder 11 is reciprocated vertically by means not shown but which are very well known in the art according to the particular type of press, and, in the present case, this member 11 is provided with a pair of downwardly depending rods 15 extending freely through the die shoe 10 and terminating at their lower ends in members 16 of greater diameter than the said rods 15, so that the upper ends of these members will provide stop shoulders 16'. These members 16 will be hereinafter referred to as "stop members," and they may be countersunk and threaded on the ends of the said rods 15 (as indicated in dotted lines in the drawings) to permit a certain amount of coaxial adjustment on the said rods 15 to vary the positional setting of the stop shoulders 16' where such adjustment may be thought necessary or desirable.

The stripper or ejector pin 17 is also shown 20 as being freely reciprocal through a guide opening 18 in the stationary die shoe 10 and having its lower end resting on a kicker element or plate 19, which normally is supported on heads of studs 20, which studs pass upwardly through the said kicker plate 19 and are secured to the under side of the die shoe 10. The kicker plate 19 is vertically slideable over the studs 20 and compression springs 21 are interposed between the upper surface of the said kicker plate 19 and the under surface of the die shoe 10. The heads of the studs 20 obviously limit downward movement of the kicker plate 19.

Secured to the under side of the kicker plate 19 are blocks 22 vertically bored at 23 to slidably accommodate the stop members 16, the kicker plate being similarly bored at 24. Each block 22 extends laterally of the rod 15 and is also vertically bored at 24' to receive an enlarged stop member 25 of a detent stud 26 which stud is biased upwardly of the table 19 by a spring 27.

Each stud 26 passes freely through the kicker plate 19 and the upper shoulder 25' of its stop member 25 and forms the stop proper. The upper end of the said stud 26 is normally spaced from the underside of the die shoe 10 as clearly illustrated in Figure 1.

Each of the blocks 22 is provided with a cross passage 28 between the two bores 23 and 24' to accommodate a movable latch in the form of a ball 29 which, according to the position of the parts, impinges either the shoulder 16' of the stop member 16 or the shoulder 25' of the stop member 25, as the case may be.

The stop member 25 may be adjustable on its stud 26 in the same manner as described with

reference to the adjustment of the stop member 16 on the rod 15.

Referring now to Figure 1, it will be noted that the arrows are intended to indicate that the upper die holder of the press carrying the die element 13 is moving downwardly in the performance of its working stroke, so that corresponding movement of the rods 15 has caused the shoulders 16 of the stop members 16 to pass below the balls or latches 29 which thereby roll into impingement with the said shoulders 16' as result of the springs 27 being free to raise the stop members 25, as clearly shown in the said Figure 1. In this position of the parts, both the springs 21 and the springs 27 are fully extended, and the upper ends of the studs 26 are spaced from the underside of the die shoe 10, the ejector pin 17 being in a retracted position wherein its upper end is materially below the work 14.

As a result of this locking of the balls 29 in this impinging position, subsequent vertical movement of the rods 15 (upon the upward movement of the die holder 11 as indicated by the arrows in Figure 2), causes the said stop members 16, through the impinging latch balls 29, to raise the kicker plate 19 and compress, first, the springs 21 and subsequently the springs 27, as the studs 26 contact the underside of the die shoe 10.

Thus, continued upward movement of the die holder 11 will result in the stop members 25 of the detent studs 26 passing downwardly through the bores 24' of the blocks 22 as the said springs 27 are further compressed. This relative movement of the stop members 25 downwardly through the said bores 24' eventually permits the latch balls 29 to move inwardly of the bore 24' and along the cross passage 28 out of the path of the shoulder 16' of the stop member 16, which thus permits the springs 21 to urge the kicker plate 19 downwardly over the said stop members 16 until the said plate 19 again comes to rest against the heads of the studs 20.

The balls 29 are now held in impingement with the shoulders 25' of the stop members 25 by the stop members 16, maintaining the springs 27 of the detent studs 26 in a partially compressed condition even though the upper ends of these studs are still in spaced relation to the under side of the die shoe 10; but, as the upper die holder 11 again descends for its next forming operation, the downward movement of the stop members 16 of the rods 15 will cause their shoulders 16' to again pass the balls 29, whereupon the action of the springs 27 will raise the stop members 25 in their bores 24' and so permit these stop members 25 to move and lock the balls 29 in impingement with the shoulders 16' of the stop members 16, the cycle of operations being repeated as the press operation is continued.

Obviously the described motion of the kicker plate 19 is transmitted to the ejector pin 17 so that the upper end of this pin will dislodge or eject the work 14 from the lower die member 12 as the return movement of the die member 11 opens the dies and raises the kicker plate 19 in the manner described, the said ejector pin 17 simply descending (as by gravity in the illustrated example) with the said kicker plate whenever it is moved downwardly by the action of the springs 21 as described.

It will be understood that while the press embodying the invention has been described as vertical, the arrangement is quite adaptable to presses or machines of an inclined or horizontal

nature. Furthermore, while the two stop assemblies are illustrated as providing a desirable balancing of forces about the working center of the press, one or any desired number on such assemblies may be utilized, according to the size and type of press and the position of the dies thereof. The disappearing ejector pin may serve to completely eject work from the machine or to merely loosen or displace it to an extent whereby it is readily removed from the dies without necessarily interfering with the continuous operation of the machine.

This invention may be developed within the scope of the following claims without departing from the essential features of the said invention and it is desired that the specification and drawing be read as being merely illustrative of a practical embodiment of the invention and not in a strictly limiting sense.

What I claim is:

1. In combination with the upper die holder and lower die shoe of a press, a kicker plate mounted in spaced relation beneath said die shoe, a work-dislodging element perpendicularly guided in said shoe and carried by said plate, means biasing said plate away from said die shoe, a housing carried by said plate, a reciprocal rod extending perpendicularly through said housing, a reciprocal stud in parallel spaced relation to said rod also extending through said housing with its upper end normally spaced relative to the under side of said die shoe, said stud being biased in the direction of said shoe, a detent guided laterally in said housing, and bevelled stop members on said rod and on said stud for alternately engaging said detent as said stud is moved against its bias by contact with said shoe or is in its normal position free of said shoe, whereby said detent is normally held in impingement with the shoulder of the stop member of said rod until released by said movement of said stud.

2. In combination with the upper die holder and lower die shoe of a press, a kicker plate mounted in spaced relation beneath said die shoe, a work-dislodging element perpendicularly guided in said shoe and carried by said plate, means biasing said plate away from said die shoe, a reciprocal housing carried by said plate, a rod extending perpendicularly from said holder through said housing, a reciprocal stud in parallel spaced relation to said rod also extending through said housing with its upper end normally spaced relative to the under side of said die shoe, said stud being biased in the direction of said shoe, a detent guided laterally in said housing, and bevelled stop members on said rod and on said stud for alternately engaging said detent as said stud is moved against its bias by contact with said shoe or is in its normal position free of said shoe, at least one of said stop members being mounted for adjustment in the direction of the press motion, whereby said detent is normally held in impingement with the shoulder of the stop member of said rod until released by said movement of said stud.

3. In combination with the upper die holder and lower die shoe of a press, a kicker plate mounted in spaced relation beneath said die shoe, a work-dislodging element perpendicularly guided in said shoe and carried by said plate, means biasing said plate away from said die shoe, a reciprocal housing carried by said plate, a rod extending perpendicularly from said holder through said housing, a reciprocal stud in parallel spaced relation to said rod also extending through said

housing with its upper end normally spaced relative to the under side of said die shoe, said stud being biased in the direction of said shoe, a detent guided laterally in said housing, and bevelled stop members on said rod and on said stud for alternately engaging said detent as said stud is moved against its bias by contact with said shoe or is in its normal position free of said shoe, whereby said detent is normally held in impingement with the shoulder of the stop member of said rod until released by said movement of said stud, said stop members being mounted for adjustment in the direction of the press motion.

DOMINIC MANIACI.
